MATERIAL HANDLING DEVICE AND
METHOD

Millington E. Stair, Chicago, Ill., assignor to
Wyman-Gordon Company, Harvey, Ill., a cor-
poration of Massachusetts

Application October 26, 1949, Serial No. 123,619

5 Claims. (Cl. 294—74)

1

This invention relates, in general, to a material handling device and method, and is particularly concerned with a cable sling, clamp, and method for handling articles in industrial operations.

While the particular device which I shall describe hereinafter in connection with the drawings is a cable sling device adapted for use in handling crank shafts, it is to be understood that the present invention is not in all of its aspects limited to such use, but may be employed for all similar purposes.

It is well known in industrial operations to stack various material on pallets and to ship the pallets with the stacked material, the pallets being later returned. Pallets which have been used for shipping crank shafts of the character with which the present invention is adapted for use are bulky and weigh about 118 pounds. The return freight on a single pallet from Detroit to Chicago amounts to eighty cents which, when the pallet is used to ship, for example, forty crank shafts, increases the cost two cents for each crank shaft. The weight of the pallet also increases the cost of shipment with the crank shafts.

One of the main objects of the present invention is to provide an improved sling handling method; also an improved form of cable sling which is less bulky and of considerably less weight than the pallets, skids and the like heretofore employed for handling articles of the character with which the present invention is particularly adapted for use.

Another object of the present invention is to provide a sling device which may be readily applied, for example, around relatively bulky and heavy and loosely stacked articles, such as crank shafts or the like; the sling being of a character to bind the articles together and to be shipped therewith; also of a character to be readily removed and returned to the shipper at considerably less expense than has been incurred where pallets, skids and the like have been used in handling such articles.

Another object of the invention is to provide the sling with an improved form of cable clamp which is adapted when the cable is applied around the articles and drawn tight to clamp the cable tightly about the articles for shipping in stacked form, with the cable secured about the articles and binding them tightly together; also an improved form of cable clamp that may be conveniently released for removal of the sling from the articles.

2

Another object of the invention is to provide an improved form of cable clamp having a novel and improved cam action for gripping the cable between cooperating cable gripping surfaces of the clamp, and, more particularly, cable gripping surfaces for securely gripping the cable without severing or destroying the cable.

Another object of the invention is to provide an improved form of cable clamp having a handle 10 for releasing the locking member of the clamp for engagement with the cable, and, more particularly, a handle disposed so that if other articles are placed on the articles bound together by the cable sling, any action of such other articles on the handle will tend to swing the locking member of the clamp in a direction to increase the locking engagement with the cable.

Another object of the invention is to provide an improved form of device of the character set 20 forth having various features of novelty and advantages, and which is particularly characterized by its simplicity in construction and its effectiveness in use.

Further objects and advantages of the invention 25 will appear from the following detailed description taken in connection with the accompanying drawings which illustrate the manner of constructing and using an illustrative embodiment of the invention.

30 In the drawings:

Figure 1 is a view showing in end elevation one of the stacking cradles and a plurality of crank shafts at the stage where the sling embodying the present invention has been applied around 35 the crank shafts and is being lifted by a lifting or elevating mechanism;

Figure 2 is a perspective view of one of the stacking cradles;

Figure 3 is a fragmentary detail view showing 40 how the cable is applied to the cable clamp and the manner in which the cable clamp operates to lock the cable tightly about the articles;

Figure 4 is an end view of the cable clamp looking in the direction of the arrow A in Figure 3; and

Figure 5 is an end view of the cable clamp looking in the direction of the arrow B in Figure 3.

Referring to the drawings, according to the present invention the crank shafts 1 or other articles are stacked in a pair of cradle members 2, one of which is shown in end elevation in Figure 1 and in perspective view in Figure 2.

Each cradle 2 has feet or base portions 3 adapted to rest on the floor, ground, or other support, and a generally U-shaped and upwardly

opening frame 4. The bottoms 5 of the frames 4 support the crank shafts in elevated position above the floor or other support, and the up-standing sides 6 retain the crank shafts in loosely stacked relation as they are placed in the cradles. The cradles 2 are disposed in spaced relation for the stacking of the crank shafts therein.

The cable sling comprises a cable 7 or like element, such, for example, as a rope, having at one end a loop 8 which is engaged with a hook 9 integral with a member 10 which constitutes one part of the cable clamp or locking device. Member 10 is forked at 11, and a locking member 12 is pivoted at 13 in the forked part of the member 10. A cable gripping surface is provided at 14 between the sides of the fork 11, and at the inner end thereof. This cable gripping surface 14 is preferably of smooth concave form as shown in Figures 4 and 5, and is preferably disposed at an angle of about 15° to a perpendicular to the longitudinal center line of the member 10.

The locking member 12 has a curved peripheral cable gripping surface 15 between which and the gripping surface 14 of the clamp member 10 and the sides of the fork 11 the cable 7 is passed upon passing the cable around the stack of crank shafts or other articles 1 and applying the loop 8 of the cable to the hook 9. The peripheral gripping surface 15 is preferably of smooth, concave form, as shown in Figures 4 and 5. The previously mentioned angle of the cable gripping surface 14 is in a direction downward and away from the cooperating cable gripping surface 15 as the device is viewed in Figure 3. This angularity of the surface 14 is important because, if the angularity is too much less than that described, the cam surface 15 will not come into full bearing, and the clamp will not effectively lock the cable. On the other hand, if the angle is in the opposite direction, the clamp will not lock the cable at all.

The locking member 12 has a protruding arm 16 which engages the cable 7 ahead of the cable gripping surfaces 14 and 15 in the direction of the stacked articles 1, as shown in Figures 1 and 3, to provide by its cooperation with the cable a lever action for imparting swinging movement to the locking member 12 in a direction to produce gradually increasing and tight gripping engagement of the cooperating gripping surfaces 14 and 15 with the cable. The protruding arm 16 constitutes, in effect, a lever which derives its force from the tension within the cable. As shown in Figure 3, the curved peripheral cable gripping surface 15 of the locking member 12 is of generally increasing radius in the direction of the arrow C. As a result, when the locking member 12, as viewed in Figure 3, is swung counterclockwise about the pivot pin 13 by the cooperation of the cable 7 with the protruding arm 16 of the locking member, the gripping surface 15 wedges very firmly into engagement with the cable to grip and lock it tightly between the gripping surfaces 14 and 15.

As shown in Figure 4, the pivot pin 13 is headed at one end at 16'. The opposite end of the pin 13 passes through a washer 17 and is secured in place, for example, by a cotter pin 18 which is passed through a diametrical aperture 19 near the end of the pin 13. A stop pin 20, integral with the locking member 12, cooperates with the end 21 of the clamp member 10 to limit swinging movement of the locking member 12 clockwise relative to the member 10 as the cable clamp is viewed in Figure 3. The smooth, concave form

5 of the gripping surface 15 preferably extends throughout the entire extent of the curved peripheral gripping surface and down and around the protruding arm 16 of the locking member 12 as shown in dotted lines in Figure 3.

For the purpose of tightening the cable 7 about the stacked articles and lifting them from the cradles 2, there is shown fragmentarily in Figure 1 a lift truck 22 having a frame which is vertically movable, as well known in the art. This vertically movable frame has an outwardly extending horizontal arm or boom 23 which may be extensible horizontally as shown, although the extensible features of the boom 23 may be omitted. The boom 23 carries a swivel hook 24, and the adjacent end of the cable 7 has a loop 25 which is engaged with the hook 24.

20 In handling the crank shafts 1 or other articles according to the present invention, they are first loosely stacked in the cradles 2. The looped end 25 of the cable is then engaged with the swivel hook 24, and the cable is passed down around the stacked articles 1 and the looped end 8 of the cable is engaged with the hook 9 on the clamp member 10.

25 The boom 23 is then raised and thus draws the cable 7 tightly around the articles 1, and continued upward movement of the boom lifts the bound articles from the cradle 2. Then when the articles are set down, for example, on a truck or on the floor or other support, the spreading action of the cable on the grooved protruding arm 16 of the locking member 12 swings this member counterclockwise about the pivot 13 as the device is viewed in Figure 3. As a result, the setting down of the articles after the cable is drawn tightly about the articles causes the grooved peripheral surface 15 of the locking member 12 to be wedged very firmly against the cable 7, at 26, to clamp and lock the cable securely between the grooved surface 15 and the opposed grooved gripping surface 14 of the clamp member 10. This clamps or locks the cable 7 tightly and securely about the stacked articles.

30 40 45 For crank shafts which heretofore required pallets weighing about 118 pounds, the cable and locking device of the present invention may weigh as little as six pounds, and the cable and locking device are less bulky than the pallets, skids and the like previously employed.

50 55 60 The locking member 12 has an integral angular handle 27 which may be grasped in the hand and swung in a clockwise direction as viewed in Figure 3, to release the locking member 12 and thereby the cable 7 for removal from the articles, for example, after they reach their destination, or at any other desired time. The handle 27 is so disposed that if other articles are stacked or placed on the articles bound by the cable sling, any downward action of such other articles on the handle 27 will tend to swing the locking member 12 in a direction to increase its locking engagement with the cable 7.

65 70 The cable clamp of the present invention is not limited to use as a locking choker for sling handling articles, but may be used for any other desired purpose, for example, with a single cable for lashing vehicles or cargo to vessels, freight cars or the like, or for securing airplanes to the ground, or for any other purpose.

75 The embodiment of the invention shown in the drawings is for illustrative purposes only, and it is to be expressly understood that said drawings and the accompanying specification are not to be construed as a definition of the limits

or scope of the invention, reference being had to the appended claims for that purpose.

I claim:

1. A cable clamp for clamping a cable in looped relation about a bundle of articles comprising, in combination, a clamp member for attachment to one end of the cable, said clamp member having a fork thereon, a cable gripping surface between the sides of the fork at the inner end thereof, a locking member pivoted in said fork and having a curved peripheral cable gripping surface between which and the gripping surface of the clamp member and the sides of the fork the cable is adapted to pass and be gripped upon being looped about the articles, said locking member having a first protruding arm for engaging the cable in position spaced from the place of gripping engagement with the cable toward the looped portion thereof whereby the articles act automatically to swing the gripping surface of the locking member into gripping engagement with the cable, and a second protruding arm on said locking member for swinging the locking member in a direction to release the gripping engagement with the cable, said second arm being positioned where upon looping the cable about the articles it will be disposed outside the looped portion of the cable which encircles the articles so that it will not be operated to released position by the articles within the looped portion of the cable.

2. A cable clamp according to claim 1 wherein there are stop means on the locking member co-operable with the clamp member to limit the releasing movement of the locking member to pre- 35

vent jamming the cable against the clamp member at position spaced from the place of gripping engagement with the cable.

3. A cable clamp according to claim 1 wherein the curved gripping surface of the locking member has side flanges cooperating with the cable to prevent the same from slipping sidewise from the locking member.
4. A cable clamp according to claim 1 wherein there is a hook on the clamp member for quick detachable engagement with a fixed eye at one end of the cable.
5. A cable clamp according to claim 1 wherein there is a hook on the clamp member for quick detachable engagement with a fixed eye at one end of the cable and the cable gripping surface between the sides of the fork of the clamp member is disposed obliquely relative to a line intersecting the pivot for the locking member and the center of the cable engaging portion of the hook.
